Inventor,

Charles M. Johnson

per *A. B. Upsham*,

His Attorney.

UNITED STATES PATENT OFFICE.

CHARLES M. JOHNSON, OF PEORIA, ILLINOIS, ASSIGNOR TO WILLIAM S. LAMSON, OF LOWELL, MASSACHUSETTS.

CASH-CARRIER FOR STORES.

SPECIFICATION forming part of Letters Patent No. 295,645, dated March 25, 1884.

Application filed January 14, 1884. (No model.)

To all whom it may concern.

Be it known that I, CHARLES M. JOHNSON, of Peoria, in the county of Peoria, in the State of Illinois, have invented an Improvement in 5 Cash-Carriers for Stores; and I do hereby declare that the following is a full, clear, and exact description thereof, reference being had to the annexed drawings, making a part of this specification, in which like letters of reference refer to like parts, and in which—

Figure 1 represents a side elevation; Fig. 2, a sectional elevation at *xx*.

My invention is in that line of cash-carriers in which inclined tracks or ways suspended 15 above the counters of a store, and terminating at one end at the cashier's desk, are provided with trap-doors, which are automatically opened by the arrival thereat of the rolling ball belonging thereto.

20 My invention relates to means whereby several balls, all of the same size, may roll upon a single track and each open its own trap-door alone; also, to so adapt a single elevator to receive as well as elevate a ball.

25 My means for operating the trap-doors consist, essentially, in having the balls of different weights and adapting the traps to be unlocked by mechanism which acts under the weight of its own ball alone. To do this I have a slight elevation in front of each trap, which is depressible only under a given weight. This movement of depression I make to act directly upon the lock to release the trap, and therefore have the heaviest ball belong 30 nearest the cashier, or else the ball which is too light to depress said elevation strikes a lever suspended above or completes an electric circuit, and so unlocks its trap. The heavier balls, by depressing the elevation, do not strike 35 said lever, and so do not release the catch. In this case the heaviest ball goes to the station the farthest from the cashier.

In the drawings I show simply the means whereby the depression of an elevation shall 40 act directly to unlock the trap.

A is the track running to the cashier, and B the track from the cashier to the clerks, only one trap, C, and elevator being shown.

45 A short distance in front of the trap C is a tongue, pivoted at one end to the track-rails B, and resting at its other extremity upon the

horizontal arm of the angle-iron H. From the lower arm of said angle-iron runs a slender rod, E, to the latch D. Said latch D, pivoted to the frame-work of the cage F, is adapted to engage with the trap C and hold it in place when closed. The spring S serves to hold said latch against the pressure of all the balls except the one belonging thereto.

As shown in Fig. 2, the cage F is curved toward the elevator L, and the side M of said elevator is low, so that when a ball falls through the trap C it is directed laterally into the said elevator L. This elevator is retained in position to receive the ball from the cage F 60 by means of the cord R', passing up over the pulley and down to the weight W, suspended by a cord, R'', from the ceiling. When reinforced, however, by the ball, the elevator overpowers the weight W and sinks to the end 65 of its rods O N. Here the terminally-enlarged lug T sinks in between the springs T', and holds the elevator while the ball is removed, its contents attended to, and it returned thereto.

To send the ball to the cashier the elevator 70 is raised by the cord R or other means until its floor is on a level with the switch-track A', the angle-iron K strikes the projection O', and the ball is thrown thereby from the elevator to the said switch-track A', and from thence 75 to the track A. The weight W being supported by the cord R'', the cord R' is hanging slack, and the elevator is held by the cord R alone. Now, when the clerk releases the cord R, the elevator sinks down to the level of the cage 80 F, at which point it is held by the weight W, the cord R', connecting therewith, having now become taut. The trap C, which is pivoted at its center to the track-rails, is provided 85 with the rigid arm C', and the lower end of said trap weighted to enable it to open when the latch D is unlocked.

As the properly-weighted ball comes rolling down the track B, it passes over the tongue G, and depresses the same sufficiently to release, through the angle-iron H and rod E, the trap C from its retaining-latch D. Said trap at once opens to the position shown in Fig. 1, the ball drops therethrough, in its fall strikes upon the arm C', thereby closing the trap, and passes down 90 through the cage F into the elevator L, which sinks with it to the clerk.

What I claim as my invention, and for which I desire Letters Patent, is as follows, to wit:

1. In a cash-carrier, a track having several balls or other carriers of different weights thereon, in combination with traps in said track, and means whereby the weights of said balls shall each open its own trap alone.
2. In a cash-carrier, a track having a trap, and a slight elevation a short distance in front of said trap, in combination with means, substantially as described, whereby the depression of said elevation shall unlock said trap, for the purpose set forth.
3. The track B, having trap C and tongue G, in combination with the latch D, spring S, and means whereby the depression of said tongue shall release said latch, substantially as and for the purpose specified.
4. The track B, trap C, and tongue G, in combination with the angle-iron H, rod E, latch D, and spring S, substantially as set forth.
5. The track B, trap C, and laterally-curved cage F, in combination with the elevator L, having low side M, and means for raising the same.

6. The track B, trap C, and laterally-curved cage F, in combination with the elevator L, having low side M, rods O N, switch-track A', and track A, substantially as described.

7. The track B, trap C, and cage F, in combination with the elevator L, having low side M, cords R and R', pulley P, and weight W, having supporting-cord R".

8. In combination with the elevator L, rods O N, and cord R, the terminally-enlarged lug T and springs T', for the purpose set forth.

9. In combination with the track B, having trap C, curved cage F, and track A, having switch-track A', an elevator adapted to receive a ball from said cage and deliver it at said switch-track, substantially as and for the purpose described.

In testimony that I claim the foregoing invention I have hereunto set my hand this 10th day of January, 1884.

CHARLES M. JOHNSON.
